United States Patent Office.

CALEB CONDERMAN, OF HORNELLSVILLE NEW YORK.

Letters Patent No. 65,876, dated June 18, 1867.

IMPROVEMENT IN CARRIAGES.

The Schedule referred to in these Letters Patent and making part of the same.

TO ALL WHOM IT MAY CONCERN:

Be it known that I, CALEB CONDERMAN, of Hornellsville, in the county of Steuben, and State of New York, have invented a new and useful Improvement in Carriages; and that the following description, taken in connection with the accompanying drawings, hereinafter referred to, forms a full and exact specification of the same, wherein I have set forth the nature and principles of my said improvements by which my invention may be distinguished from all others of a similar class, together with such parts as I claim and desire to have secured to me by Letters Patent.

The present invention relates to that class of carriages commonly known as open frame and light buggies, and the invention consists in a novel manner of securing or suspending the body of the buggy to the axles by and through the means of springs, as will be hereinafter particularly described, reference being had to the accompanying plate of drawings, in which—

Figure 1 is a longitudinal vertical section through the carriage body; and

Figure 2, a transverse vertical section taken in the plane of the line x x , fig. 1.

A, in the drawings, represents the frame or body to the buggy, and B and C respectively the front and rear axles on which the body is to rest, extending across from one to the other. This body is supported upon the axles B and C, by and through longitudinal springs E, one upon each side. These springs are secured at their centre points to the centre of the body, and as they extend along under the body for its length they afford a support to it, and enable a much lighter body to be used with all the requisite amount of strength and stiffness, as well as affording an easy, comfortable, and most desirable riding to the carriage. F, the seat to the body supported at each end upon round springs G, and at the centre point of the body springs E.

Having thus described my invention, I claim as new, and desire to secure by Letters Patent—

The springs E, in combination with the body or frame A, substantially as and for the purpose described.

CALEB CONDERMAN.
